JOHN GOOD, OF BROOKLYN, NEW YORK, ASSIGNEE TO GOOD INVENTIONS CO., OF BROOKLYN, NEW YORK, A CORPORATION OF NEW YORK.

FUEL-CHARGE-SUPPLY APPARATUS.

1,253,681.

Specification of Letters Patent. Patented Jan. 15, 1918.

Application filed June 1, 1916. Serial No. 101,017.

To all whom it may concern:

Be it known that I, JOHN GOOD, a citizen of the United States, residing in Brooklyn, New York, N. Y., have invented the following described Improvements in Fuel-Charge-Supply Apparatus.

My invention is concerned with the uniformity of the supply and the character of the combustible mixture of liquid fuel and air supplied to internal combustion engines, particularly automobile and marine engines, and consists essentially in constituting a portion of the length of the suction intake between the engine and the charge-forming device or carbureter, as a Venturi-tube, so that the entire mixture charge must pass through such tube after its measurement in the carbureter, whereby the vaporization of the mixture and its homogeneity are greatly improved, with corresponding improvement in the engine efficiency, and whereby also the liquid fuel to form the mixture may be brought from a storage tank at a lower level to a local service tank at a higher level, from which it may flow by gravity and under substantially constant head to the carbureting spray nozzle thereby assuring constant conditions for the formation of the mixture. The improvement in the combustibility of the charge mixture results from the combination of the two conditions of high velocity and sharp pressure reduction occurring at the throat of the Venturi-tube accompanied also by the deposition of the liquid spray on the wall of the tube as it passes through, and the consequent film-vaporizing action that occurs in such passage. It is necessary for this purpose that substantially the entire charge, in the form of a previously formed spray mixture, enter the convergent entrance of the Venturi-tube. In the accomplishment of the uniformity of liquid supply, the invention consists in the combination of the same Venturi-tube with a local service tank having suitable automatic controlling agencies whereby the pressure depression existing at the throat of the Venturi is caused to supplement the normal relative vacuum in the suction intake and create vigorous liquid flow to said local tank from the main supply at a lower level under all conditions of use and independently of the adjustment of the engine throttle. Local service supply tanks of this kind, operated by the relative vacuum in the suction intake are already well known.

to the art and I prefer to employ my present invention with that type of local service tank shown and described for example in the patent to Webb Jay, No. 1,158,924, dated November 2, 1915. Such apparatus is provided with the usual double chamber construction, a float valve, and suitable pipe connections to the suction intake and the main supply tank and, under the control of the float valve, operates intermittently to allow the vacuum in the suction intake to draw the liquid fuel from the main tank into the upper chamber of the local tank from whence it flows into the lower chamber and thence to the carbureter spray nozzle. In such apparatus, as now and heretofore used, vacuum conditions normally existing in the suction intake depend principally upon the position of the engine throttle which controls the flow therethrough, a closed throttle creating a very considerable relative vacuum. When the throttle is full open, or nearly full open, however, the relative vacuum in the suction intake is, of course, very much less and is too slight of itself to effect the desired suction operation and such reduced suction frequently coincides with working conditions requiring the maximum fuel supply, that is to say, maximum fuel is needed when the throttle is wide open, so that the fuel is thus apt to fail when most needed. This objection is not apparent in automobiles where the throttle is seldom full-open and never full open for very long periods, and where the capacity of the local tank is made large enough to accommodate the maximum expected full open operation, but in marine engines where a wide open throttle is the normal position the said apparatus cannot be practically used for obvious reasons, and even with liberal tank capacity are uncertain of operation for automobiles under certain conditions, such for example as when the loaded engine with wide open throttle is ascending a very long hill. By the present invention the minimum degree of relative vacuum available to lift the fuel is always sufficient for the purpose whether the throttle is wide open or not and the increased vacuum is obtained not only without imposing any appreciable restriction to the flow of the charge mixture to the engine but actually improving the character of the mixture so that it is capable of more efficient combustion and thereby the

utility of apparatus of the kind referred to and the engine plant as a whole is materially increased, and the utility of the said apparatus is extended to fields in which it has not 5 heretofore been available, to wit, motor-boats and conversely smaller local tanks may be used in automobile service with the same or better results than heretofore.

In the accompanying drawings I have 10 shown such a service tank as above referred to and as shown in the said patent of Webb Jay combined with a Venturi tube constituting part of the suction intake manifold of an engine in accordance with my invention, 15 Figure 1 being the general organization, and Fig. 2 being a modified form.

The engine illustrated in outline may be assumed to be an ordinary automobile engine having a suction intake manifold 1 20 connected with a carbureter 2 of any desired or suitable type by means of a Venturi tube 3. This tube comprises a relatively abruptly convergent entrance section 4 and a longer divergent recovery portion 5 the 25 widest diameter of each section being equal to the general diameter of the suction intake passage as a whole. The taper of both sections is determined according to the known principles of Venturi tube construction, with 30 reference to the normal flow through the engine intake and to produce a local region of sharp pressure reduction at its throat or narrowest point without however producing any appreciable obstruction to flow by reason 35 of the narrow diameter at the throat, and that being the characteristic of Venturi-tubes as distinguished from other constricted passages. The local reduction of pressure at the throat is accompanied by corresponding 40 local increase of the flow velocity and these two coincident conditions are conducive to rapid and complete vaporization of the liquid fuel in the air and thorough mixing of the vapor therewith. It is to be noted 45 that the mixture of the liquid fuel and air is formed by and within the carbureter 2 which has the usual spray valve nozzle 6 for that purpose, so that a previously formed spray mixture in explosive proportions, that is to say, having all the fuel and 50 all the air requisite for explosive combustion in the engine cylinder, enters the tube and is directed against the convergent wall surface of the entrance section 4. The suspended liquid forms a film on this convergent surface, being assisted to such condition by deflection by the throttle 12, when the latter is located close to the entrance, 55 which is its preferred location. The film thus formed of previously air-carried liquid particles is subject to the friction of the gaseous flow and is rapidly dissipated by such mechanical action while being carried toward and through the intensely evaporative 60 region of local vacuum and high velocity

at the throat of the tube. Such mechanical action at the entrance end of the tube, is an essential factor in the function of the Venturi as a charge-perfected agent. It has been ascertained that the rate of heat transfer 70 through the walls of tubes in this relation, is increased by accelerating the gas flow through them, and the very high velocity at the throat of the Venturi of this invention materially promotes the transfer 75 of heat from the exterior of the tube in quantity adequate to satisfy the latent heat of vaporization of the fuel flowing within it, and also improves the homogeneity of the resultant mixture. By these several effects, therefore, the fuel liquid is converted, 80 more or less completely, into vapor at a relatively low temperature, and the vapor is homogeneously mixed with or impregnated 85 into the air component of the charge, which component, as above stated, flows through the tube in the full amount requisite to constitute an explosive engine mixture, no further addition of air being necessary or desirable. By as much as the resulting mixture 90 is thus relatively cool, it is correspondingly dense, which means that it contains a larger weight of fuel and air than could otherwise be the case if the same extent of vaporization were produced by the mere application of heat alone without the assistance 95 of the Venturi as above described. The Venturi tube should be thin walled and internally smooth and also devoid of internal pockets or projections of any kind likely to 100 retain the liquid fuel or form deposits, and, in order that it may give the characteristic Venturi action, the total length of its convergent and divergent sections together will 105 always be many times the diameter of its throat or narrowest part. In its preferred form it is formed with attachment flanges at its opposite ends which obviously enables it to be interposed in the suction intake of existing engines with a minimum alteration 110 to the latter. The local vacuum effect in the region of the throat is a function of the velocity of flow and the flow with wide open throttle and the engine under load is ample 115 to give an adequate vacuum effect to lift the fuel to even greater elevations than normally required, this being due to the known characteristics of the Venturi tube and without imposing any appreciable restriction to flow through the intake. The vacuum effect 120 due to partial closing of the throttle is supplemental to and not the controlling factor of the suction acting to lift the fuel. 125 The liquid receptacle of the carbureter 2 is kept at a constant level in Fig. 1 by means of the usual float controlled valve as indicated, and receives its liquid through a pipe 7 from the local service tank 8 mounted at a higher level. This tank in turn receives 130 its supply of liquid fuel through the pipe 9

from a main storage tank 10 which is to be understood as the tank commonly attached to the rear of the automobile at about the level of the rear axle, and hence below the 5 level both of the local tank 8 as well as below the carburetor. The construction and mode of operation of the local tank shown is the same as that shown and described for example in the patent above referred to and 10 to which reference may be had for a further and detailed explanation thereof. Briefly, the said tank includes an upper and a lower chamber for the liquid fuel and the upper chamber is in constant communication with 15 the storage tank through the supply line 9 and is adapted to discharge its liquid into the lower chamber through a flap-valve outlet 24. Suitably guided in the upper chamber there is a float 19 connected to and operating 20 a lever 20, and through a link 21 this lever operates a second lever 22 to which a spring or springs 23 is connected and the other end of the spring is connected to a short lever 18, the arrangement of the two 25 levers being so related to their common fulcrum that as the float rises and falls the spring is carried past the axis of the fulcrum thereby resulting in a snap movement of the short lever 18. This latter lever 18 operates 30 two valves; one of them, 16, controls the communication between the upper chamber and the suction pipe 11 and the other, 17, controls a communication between the upper chamber and the vent to atmosphere, 15. 35 The suction pipe 11 leads to the throat or point of narrowest constriction of the Venturi tube 3 above described and is therefore subject to the local pressure depression always existing at that point. The falling 40 of the float 19, which results from the discharge of the liquid in the float chamber into the lower chamber, simultaneously closes the air vent 17 and opens communication through the pipe 11 with the Venturi tube 45 and thereby the relative vacuum of the latter is extended into the upper chamber causing immediate flow of liquid fuel to that chamber against gravity from the storage tank 10. This flow continues until the float 19 50 shifts the spring 23 past the fulcrum of levers 22 and 18 whereupon the suction valve 16 is closed and the air vent valve 17 is opened thereby permitting the liquid just drawn into the upper chamber to flow by 55 gravity into the lower chamber and presently reaching a condition where the movement of the float valve takes place in accordance with the withdrawal of fuel from the lower chamber to the carburetor, that is to say, in accordance with the demands of the engine. 60 The lower chamber will be observed also to be in communication with atmosphere through the pipe 15.

The throttle 12 is interposed between the 65 Venturi tube and the carburetor 2 so that

the whole charge as formed in the latter is admitted to the Venturi tube according to the throttle adjustment.

Any type of carburetor may be used, and in Fig. 2 I have shown a modified form of 70 the same type shown in Fig. 1, but wherein the liquid level of the receptacle is kept at a predetermined height by means of an overflow circulation system, the overflow returning back to the main storage tank 10. The 75 liquid feed pipe 7, having the same connection to tank 8 as above described, delivers the liquid into the compartment 30 with a constant delivery exceeding the maximum requirement of the engine and the spray 80 nozzle 6 takes its liquid from this chamber. The excess overflowing the upper edge of the wall of the compartment 30 into the surrounding compartment 31, flows back to the tank by the return pipe 32. By this arrangement a continual circulation of the liquid fuel is established, while the engine is in operation, and the fuel in the main storage tank is thereby kept in motion, which has the effect of keeping it of a constant quality and 85 specific gravity throughout, by preventing gravitational separation or stratification of the components. When lubricating oil is added to the fuel, this circulation has the effect of maintaining a homogeneous mixture 90 therein with the fuel.

From the foregoing it will thus be apparent that the invention provides for the general improvement of the means for supplying the combustible to internal combustion engines and it remains to point out that it applies equally to all kinds of fuel, as will be evident. When using fuels heavier than ordinary gasoline, heat is applied to the fuel within the Venturi tube to accommodate and 100 facilitate its rapid vaporizing action, the heat being taken from the water-jacket of the engine or its exhaust gases, according to prior art methods and the character of fuel used, and such heat may be applied to the 110 exterior of the tube or to the air entering the same, or both, as preferred. In the case shown the heat is applied externally by enclosing the Venturi tube in a box 41 having inlet and outlet connections for the exhaust 115 gas from the engine which gas may thus flow around the tube and heat it.

I claim:

1. The combination with an internal combustion engine, of means for supplying combustible mixture of fuel liquid and air thereto, comprising a charge-forming device, a single Venturi tube constituting part of the length of the suction intake between said device and the engine, and an engine controlling throttle between said device and Venturi tube, intercepting the entire charge mixture passing to the engine.

2. The combination with an internal combustion engine, of means for supplying com-

bustible mixture of liquid fuel and air there-to, comprising a charge-forming device, a Venturi tube constituting part of the suction intake between said device and the engine, 5 and a throttle intervening between said de-vice and Venturi tube.

3. Fuel supply apparatus for internal combustion engines, comprising a charge-forming device operated by the engine suc-10 tion to deliver a mixture of liquid fuel spray and air in the explosive proportions suited for combustion in the engine, a suction intake connecting the said device to the inlet valve port of the engine and including a 15 single Venturi tube comprising a convergent entrance section which is connected to said device to receive all of the mixture produced thereby and a gradually divergent recovery or exit section which conducts such mixture 20 toward the engine, the said two sections of the tube being together many times as long as the diameter of the throat or narrowest part of said tube, and coöperating to maintain a region of local pressure reduction and 25 high mixing velocity at said throat adapted to promote vaporization of fuel liquid in said mixture without appreciable obstruction to flow through said intake, and a medium surrounding said tube for freely supplying 30 the heat for the vaporizing action therein.

4. Fuel supply apparatus for internal combustion engines, comprising a charge-forming device operated by the engine suc-35 tion to deliver a mixture of liquid fuel and air in the explosive proportions suited for combustion in the engine, a suction intake connecting said device to the inlet valve port of the engine and including a single externally-heated, Venturi tube comprising a 40 convergent entrance section which is connected to said charge-forming device to receive all of the mixture produced thereby and a gradually divergent recovery or exit section which conducts such mixture toward 45 the engine, the two sections of said tube be-

ing together several times as long as the di-50 ameter of the throat or narrowest part of said tube and coöperating to maintain a vacuum condition at said throat correspond-ing to the flow velocity therethrough, and an engine controlling throttle intercepting the flow to said tube and thereby adapted to establish an independent and auxiliary con-55 dition of vacuum throughout said intake.

5. Fuel supply apparatus for internal 55 combustion engines comprising a charge-forming device producing a mixture of liquid fuel and air in the explosive proportions suited for combustion in the engine, an engine intake connecting said device to 60 the inlet to the engine and including a single exhaust-heated tube, comprising a convergent entrance section which receives all the mixture produced thereby, and a gradually divergent recovery section which conducts 65 the mixture to the engine, the two sections of said tube being together several times as long as the diameter of the throat or narrowest part of said tube and being devoid of interior projections or pockets likely to ac-70 cumulate deposit or obstruct the flow and co-operating to produce a region of local vacuum at the throat of said tube, and an engine-controlling throttle in the intake at a point beyond the entrance to said tube. 75

6. Fuel supply apparatus for internal combustion engines, comprising a suction intake including a horizontally disposed mani-fold or header serving the engine inlet ports, a vertically disposed, heated, Venturi tube 80 connected to said header, and a carbureter connected to said Venturi tube, said carbureter being operated by the engine suction and delivering its whole mixture of liquid fuel and air into the convergent entrance 85 section of the said Venturi tube and having a throttle in control of such delivery.

In testimony whereof, I have signed this specification.

JOHN GOOD.
